CLAIM

The ornamental design for a slide bracket, as shown and described.

DESCRIPTION

FIG. 1 is a front, top and right side perspective view of a slide bracket showing my new design;

FIG. 2 is a front elevational view thereof, the rear view being a mirror image;

FIG. 3 is a top plan view thereof;

FIGS. 4 and 5 are respectively right and left side elevational views thereof;

FIG. 6 is a bottom plan view thereof;

FIG. 7 is a sectional view along lines 7—7 of FIG. 2; and

FIG. 8 is a sectional view along lines 8—8 of FIG. 2. It will be understood that the break in the middle of FIG. 1 and at one end in FIGS. 3-8 indicates that the slide bracket is of indeterminate length.
